METHOD AND APPARATUS FOR PRINTING
SOUND FILMLeon Dewan, New York, N. Y., assignor of fifty
per cent to George H. Callaghan, New York,
N. Y.

Application December 11, 1937, Serial No. 179,294

3 Claims. (Cl. 88—24)

This application is a continuation in part of the application filed January 26, 1935, Serial No. 3,635.

The present invention relates to photographic printing of sound on film and has for its object the reduction and elimination of dirt spots, scratches and grain from a negative sound track during the process of photographic transference to a positive film.

5 In this invention the object is attained solely by optical means. The negative is untreated but its image on the positive film is so manipulated that with development of the positive film the undesired dirt spots do not appear or are greatly reduced in intensity while at the same time the sound images are intact. A plurality of laterally displaced images of the negative are projected upon the positive film in a manner that irregularities in the lateral plane of the sound track 10 are canceled optically in their effect upon the finally developed positive emulsion without affecting the sound track whose values lie in the longitudinal plane.

Figures 1, 2 and 3 are diagrams illustrating the 25 principle of the invention.

Figures 4 and 5 are diagrammatic top and side views of an apparatus for carrying out the invention.

Figure 6 illustrates a variation of Figures 4 30 and 5.

Figures 7 and 8 are diagrammatic views of a modification of the invention.

Figure 9 is a diagram illustrating the effects 35 produced by the modification illustrated in Figures 7 and 8.

Figure 10 is a diagram illustrating another modification of the invention.

Due to the nature of photographic emulsion, and the dust or dirt which accumulates on film, 40 both variable width and variable density negative sound track often contain small spots or irregularities on their clear portions after development. Especially in the case of variable width track where the boundary between the black and transparent portions has a peculiar roughness 45 due to irradiation and the finite width of the recording light bar which affects high frequency and faint sounds to a considerable extent. This effect is greatly reduced in a feature about to be described. In Figure 1, illustrating roughly an ordinary variable width track, the black spots on the clear portion symbolize the dirt spots or roughness. Figure 2 shows a positive of this negative track produced, for example, by optically projecting an image of the negative track 50

upon a positive film. The spots that were formerly on a clear field are now clear areas upon a black field. If, instead of projecting a single image of the negative sound track upon the positive film, two or more images of the same negative track are projected, these images exactly coinciding longitudinally (in the direction of the length of the sound track) but slightly displaced laterally relative to each other, then those areas comprising the clear spots in Figure 2, which 10 would not have received light if only a single image were projected in the ordinary manner, now receive light from parts of the other images projected as illustrated in Figure 3 which shows one sound wave as of Figure 2, and only two 15 clear or white spots for purpose of illustration. The solid line represents one image and the dotted line another image of the same sound wave, and the shaded portions represent those parts of the spots which are restored to blackness or 20 opacity.

Naturally if one image of the negative track creates full blackness on the positive film by means of its luminous portions another similar image cannot greatly further blacken those portions of the positive film which have already been acted upon, but can, if slightly displaced, blacken the parts that have been left unilluminated by the first image. The greater the number of images that are used and the nearer they are spaced 25 laterally, the more effective is this "coverage." The images may also be spaced at unequal distances apart to cover the range of different sizes of the spots or irregularities. The images may also be of different intensities so that while one 30 or a number of images are capable of producing full photographic intensity, another weaker image would only affect the white spots when added to the light of other images, while the parts of the track on which it alone would fall 35 would be unaffected thereby due to the fact that its intensity is below that point at which the positive emulsion starts to record any light impression.

If desired, a strong image of the negative sound 40 track may be projected on the positive film to produce full or almost full opacity thereon, while one or more slightly weaker images are projected therewith, each one being displaced from the other a little nearer to the base line of the variable width sound track to cover the white spots 45 and irregularities.

The printing apparatus shown in Figures 4 and 5 may produce two images of the negative sound track on the positive film. The negative film 50

1 is illuminated by the lamp 2 and the spherical lens 3 focuses the image of the negative on the positive film 4. The printing aperture 5 in the mask 5a is half covered by a plane parallel glass plate 6 having a sharply defined edge. Thus there is imaged on the film 4 the upper half of the printing aperture 5 in one position and the lower half thereof in another position slightly displaced to one side due to the well known property of a parallel faced glass plate to displace an image to one side if the plate is presented at an angle. Since the films travel longitudinally (as indicated by the arrows) the result produced on the positive film when developed is two superimposed images laterally displaced with respect to each other in accordance with the invention.

It may be seen that additional displaced images may be produced by this means; for example the printing aperture may be divided in three parts, the upper and lower parts being covered by glass plates such as 6 presented in different angles while the center portion is imaged directly.

Where symmetric bilateral variable width track is to be printed according to the invention the plate such as 6 of Figure 4 may be as shown in Figure 6 where the parts 6a and 6b of plane parallel glass are bevelled and cemented together, the central joining line being in alignment with the center of the bilateral sound track.

Figures 7 and 8 illustrate a method of producing the results of the invention in a modified manner. The apparatus is mainly similar to that of Figures 4 and 5 except that in place of a plane parallel glass plate there is a convex cylindrical lens 7 which produces a laterally enlarged image of the sound track so that the result on the positive film 4' is a normal track imaged from the unobstructed part of the printing aperture 5' and superimposed thereon, a track enlarged in the lateral plane only by the cylinder lens 7.

Figure 9 shows the result on the positive with a bilateral variable width track. The areas of full density are those portions where both images overlap while the grey shaded areas are those covered by the normal image only. It is evident that all parts of the enlarged image are displaced from corresponding parts of the normal sized image in proportion to their distance from the center of the track. Thus for example if there is a small dirt spot in the negative film its laterally enlarged image would be nearer to the edge of the sound track on the positive film than its normal sized image and thus create the covering effect already described. Another effect may be observed in Figure 9 coinciding with that already mentioned. This is the fact that the valleys of the normal sized track are lightened by the lower intensity as indicated by the grey shaded portion, which represents that covered by the one image alone. The effect of this lower intensity is to clear or hollow out the valley where it tends to fill in as for example where high frequency sound waves are recorded. This result, of clearing or elongating the valleys without affecting the peaks, is desirable and has long been sought for in the printing of variable width track.

70 The apparatus described so far is usable for either variable width or variable density track but the modification of the invention illustrated in Figure 10 is designed to produce the general

result of the invention in a manner specially suitable for variable density sound track. The spherical lens 3" images the negative sound track of film 4" on the positive as in Figures 1 and 2 but the cylindrical convex lens 8 defocuses the image in the lateral plane, keeping the focus in the longitudinal plane intact. The image spreads laterally but the aperture of mask 9 allows only the correct width of the track to pass. Thus while the sound waves which are resolved in the longitudinal plane retain all their sharpness of definition, the images of dirt spots and scratches are covered by light from other parts of the image in the lateral plane and the result is a considerable clearing up, particularly effective in the periods of low volume where clear spots on the dark background of the positive would otherwise appear. Where reduction from 35 mm. to 16 mm. is accomplished by the modification of Figure 10 the mask 9 may have a much wider aperture proportionately since the lens 8 produces the effect of the disproportionate magnification required in transference of 35 mm. to 16 mm. sound track.

What is claimed is:

1. The method of photographically printing a longitudinally defined sound wave track from plain film which normally contains ground noise irregularities distinct from the sound waves, consisting in imaging said sound wave track upon a sensitive film, producing a plurality of superimposed images of said sound wave track which accurately coincide in the longitudinal plane to define scanning of the sound waves, and laterally displacing portions of one image relative to corresponding portions of another image to an extent substantially of the order of the size of the ground noise irregularities, whereby portions of one image shall fall upon different portions of the other image in the lateral plane. 40

2. The method of photographically printing a longitudinally defined sound wave track from film which normally contains ground noise irregularities distinct from the sound waves, consisting in imaging said sound wave track upon a sensitive film, producing a plurality of superimposed images of said sound wave track which coincide accurately in the longitudinal plane to define scanning of the sound waves, and laterally displacing portions of one image relative to corresponding portions of another image by causing the images to have unequal lateral dimensions, whereby portions of one image shall fall upon different portions of the other image in the lateral plane. 55

3. The method of photographically printing a longitudinally defined sound wave track from film which normally contains ground noise irregularities distinct from the sound waves, consisting in imaging said sound wave track upon a sensitive film, producing a plurality of superimposed images of said sound wave track which coincide accurately in the longitudinal plane to define scanning of the sound waves, and laterally displacing portions of one image relative to corresponding portions of another image so that said displaced portions are shifted away from either side of the center line of the track and toward the edges thereof, whereby portions of one image shall fall on different portions of the other image in the lateral plane. 70
